UNITED STATES PATENT OFFICE.

PERLEY R. GLASS, OF BROOKLINE, MASSACHUSETTS, ASSIGNOR TO P. R. GLASS COMPANY, OF BOSTON, MASSACHUSETTS, A CORPORATION OF MASSACHUSETTS.

FOLDING-MACHINE.

1,312,533.

Specification of Letters Patent. Patented Aug. 12, 1919.

Application filed November 1, 1918. Serial No. 260,733.

To all whom it may concern:

Be it known that I, PERLEY R. GLASS, a citizen of the United States, residing at Brookline, in the county of Norfolk and 5 State of Massachusetts, have invented certain Improvements in Folding-Machines, of which the following description, in connection with the accompanying drawings, is a specification, like reference characters 10 on the drawings indicating like parts in the several figures.

This invention relates to folding machines and is herein illustrated as embodied in a machine for folding the margin of a closed 15 vamp.

In folding the margin of a closed vamp the most difficult portion encountered is the throat at which locality stretching of the folded edge is liable to occur, particularly if 20 the throat is a narrow one. Hitherto machines for performing such work have been provided with a work-supporting arm projecting horizontally from the frame of the machine and constructed to permit the vamp 25 to be suspended from the outer end thereof. Although such machines have been operated successfully a difficulty has arisen by reason of two conflicting requirements. The cross-sectional area of the arm must be as small 30 as possible to accommodate vamps having narrow throats and at the same time the arm must be as rigid as possible so as to support the vamp firmly during the folding and fold-pressing operations.

According to the present invention the 35 vamp is supported upon the upper end of a substantially upright post of small cross-section. With this construction the cross-sectional area of the post may be made 40 smaller than is the case with the horizontal arm without lessening to the same extent the rigidity with which it supports the work. An upright post also possesses the further 45 advantage that the vamp, at the time of the folding of the throat is less liable to be stretched.

These and other features of the invention, including certain details of construction and combinations of parts will be described as 50 embodied in an illustrative machine and pointed out in the appended claims.

Referring now to the accompanying drawings:—

Figure 1 is an elevation of a machine in

which the present invention is embodied, 55 and

Fig. 2 is a perspective of a portion of the machine showing a closed vamp in the process of having its throat folded.

Mounted in an overhanging arm 5 is a 60 driving shaft 4 which may be rotated through any suitable clutch mechanism (not shown). This arm carries a snipping knife 104, a presser-foot 92, and a feeding foot 24. The feeding foot is carried by a 65 rod 36 mounted in a sleeve 38 the stem of which is pivotally held in a slide 48, said slide being connected by a link 52 with a bell-crank spacing lever 54 movement of which about the shaft 115 raises or lowers 70 the slide 48 and thereby the pivot about which the foot 24 oscillates. The stem 36 of the feeding foot 24 is oscillated and also raised and lowered by a cam (not shown) on the shaft 4 which rotates in a cam-follower carried at the upper end of the stem. The stem 96 of the presser-foot 92 is reciprocated by a second cam on the shaft 4 which engages a second cam-follower 98 on the upper end of the stem 96. The knife 80 104 is normally inoperative but may be rendered operative at any time by moving the rod 112 to the left and thereby moving a hook-shaped piece 108 between a shoulder 85 on the cam-follower 98 and a pin 109, said hook-shaped piece being suitably connected with the knife. A link 86 connected at one end to a treadle-controlled bell-crank lever 66 is connected at the other end at 114 to an arm fast to the farther end of the 90 shaft 115, the rod 112 being yieldingly connected with said arm. A second arm 116 fast to the nearer end of the shaft 115 is provided with a locking pin, the head of which is shown at 118; and this pin may be 95 caused to enter any one of a number of holes 119 formed in an enlargement on the lever 54, or the pin may be locked in inoperative position. When the arm 116 is locked to the lever 54, a downward pull on the treadle rod 100 will simultaneously throw in the knife and decrease the extent of the intermittent feeds caused by the movements of the feed foot 24. When the arm 116 is not locked to the lever 54, a downward pull on the rod 68 will 105 throw in the knife without affecting the extent of the intermittent feed movements.

Mounted on an upright post 201 and adapted

to coöperate with the feeding foot 24 is an oscillating block 26 the upper edge of which passes through a slot in a plate 8 mounted on the top of the post. This block is angularly movable about the axis of the screw 27 and is normally held in rearward position with reference to the feed movement of the work by a spring (not shown) but swings forwardly with the feeding foot and the stock during each intermittent forward movement of said foot. An anvil 20, mounted on the plate 8, supports the work during the pressing of the fold; and a gage 12 and plow 40 also mounted on the plate 8, serve respectively to guide the work by engagement with its edge and to form the fold.

The construction which has been thus briefly outlined, with the exception of the post 201, is or may be the same as that shown and described in application Serial No. 5245 filed in my name and will not be described further in detail.

In the machine of the prior application the plate 8 and its associated members are carried at the end of an arm which projects horizontally from the frame of the machine. In the present machine they are mounted, as has been stated, upon the top of an upright post 201. In the illustrative machine this post is integral with the frame of the machine and extends upwardly from the base thereof, there being on all sides of it a free and unobstructed space to facilitate the handling of a closed vamp. This post, as well as the frame, of the machine, is hollow; and extending down through the post is a link 203 upon the upper end of which is carried a fold-presser 205 which coöperates with the inclined anvil 20 in pressing the fold. At its lower end the link 203 is pivoted to one end of a rocker arm 207, said rocker-arm being pivoted at 209 to the frame of the machine and at its other end at 211 to the lower end of a rod 213. An eccentric strap 215 on the upper end of the rod encircles an eccentric (not shown) on the shaft 4. In order to guide the movement of the fold-presser 205 a short link 217 is pivotally connected at one end to the link 203 and at the other to a lug on the post 201 as shown. With this construction, rotation of the shaft 4 will cause the fold-presser to be vibrated in the desired manner.

The operation of the machine is as follows:

The presser-foot is raised by manipulating a finger-lever 102, and the inner margin of the vamp (usually at some locality near the rear end of the vamp) placed against the gage 12, the vamp being thus suspended on the top of the post 201 with the greater portion of the vamp hanging down below the level of said top. Power is then applied to the shaft 4, the vamp being fed intermittently by the action of the feeding foot

24 and presser-foot 92 to the plow and fold-presser in the usual manner. The inner margin of the closed vamp is thus operated upon until the starting point has been reached again and the entire margin has been folded. During the folding of the throat it is usually desirable to throw in the snipping knife and decrease the rate of feed, both of which may be accomplished by operating a treadle (not shown) which is attached to the treadle-rod 68. As has been explained, the throat of the vamp presents the greatest difficulty owing to the liability of the edge to be stretched at this locality. By reference to Fig. 2 it will be seen that with the present construction, when the throat is being folded the vamp may be swung, as indicated by the arrow, in a curved path about the axis of the post or about an axis parallel to that of the post, and that this swinging movement by reason of the post construction and the free space about the post, may take place substantially without interference so that the curve of the throat of the vamp is not distorted during the folding thereof.

Although the invention has been set forth as embodied in a particular machine, it should be understood that the invention is not limited in the scope of its application to the particular machine which has been shown and described.

Having thus described my invention, what I claim as new and desire to secure by Letters Patent is:

1. A folding machine, having in combination, a post of small cross-section provided with a work-supporting surface on the top thereof, there being a free and unobstructed space around said post, means for feeding a piece of work over said surface, means for forming a fold in the margin of the work, and means for pressing the fold.

2. A folding machine, having in combination, a post of small cross-section provided with a work-supporting surface on the top thereof, there being a free and unobstructed space around said post, a stationary member extending into proximity to the support, and mechanism for feeding the work, folding the margin thereof and pressing the fold, said mechanism being mounted upon the adjacent ends of said member and post.

3. A folding machine, having in combination, a post of small cross-section provided with a work-supporting surface on the top thereof, there being a free and unobstructed space around said post, an arm overhanging the post, and mechanisms for feeding the work, folding the margin thereof and pressing the fold, said mechanisms being mounted upon the adjacent parts of the post and arm.

4. A folding machine, having in combination, a post of small cross-section provided

- with a work-supporting surface on the top thereof, there being a free and unobstructed space around said post, an arm overhanging the post, and mechanisms for feeding 5 the work, folding the margin thereof and pressing the fold, said mechanisms being mounted upon the adjacent parts of the post and arm and including a fold presser mounted on the post.
- 10 5. A folding machine, having in combination, a post of small cross-section provided with a work-supporting surface on the top thereof, an overhanging arm, and feeding, folding and fold-pressing elements mounted
- on the adjacent ends of said post and arm 15 including a fold-presser, and means mounted on the post for vibrating said fold-presser.
6. A folding machine, having in combination, a post of small cross-section provided with a work-supporting surface on the top 20 thereof, an overhanging arm, feeding and folding elements mounted on the adjacent ends of said post and arm, a fold-presser, and mechanism extending through the post for vibrating the fold-presser. 25

In testimony whereof I have signed my name to this specification.

PERLEY R. GLASS.
